UNITED STATES PATENT OFFICE.

EUGENE H. CONANT AND GEORGE F. CONANT, OF CAMDEN, NEW YORK.

KNOCKDOWN ROCKING-CHAIR.

SPECIFICATION forming part of Letters Patent No. 229,097, dated June 22, 1880.

Application filed November 29, 1879.

To all whom it may concern:

Be it known that we, EUGENE H. CONANT and GEORGE F. CONANT, of Camden, in the county of Oneida and State of New York, have 5 invented a new and useful Improvement in Knockdown Rocking-Chairs, of which the following is a specification.

Figure 1 is a perspective view of our improvement. Fig. 2 is a sectional elevation of 10 the chair in a knockdown state.

Similar letters of reference indicate corresponding parts.

The object of this invention is to furnish knockdown rocking-chairs so constructed that 15 they may be closed into compact shape for transportation and may be conveniently put together for use.

The invention consists in constructing a rocking-chair with its front posts pivoted at 20 their upper ends to the upper parts of the rear posts, and connected at their lower parts by a pivoted round provided with upright bars to enter holes in the front round of the seat-frame, the said seat-frame being pivoted at its 25 rear corners to the rear posts, so that the chair may be closed by raising the seat-frame off the said upright bars, as will be hereinafter fully described.

A are the rear posts, which are connected 30 at a little distance from their lower ends by a round, B.

The upper and middle parts of the posts A are connected by two rounds, C, to which, at 35 a little distance from their ends, are attached two side bars, D.

The round C and bars D form the back-frame. To the top round, C, are attached the lower ends of three (more or less) short uprights, E, to the upper ends of which is attached 40 a short cross-bar, F, to form an ornamental top to the chair.

To the outer sides of the upper parts of the posts A are pivoted the upper ends of the forward posts, G. The posts G are inclined and 45 slightly curved to bring their lower ends into proper position.

The lower ends of the posts A G, or tenons formed upon the said ends, enter holes in the rockers H.

The forward posts, G, at a little distance 50 from their lower ends, have round holes formed through them to receive round tenons formed upon the ends of the round I, which is secured in place by screws J, screwed into the ends of the said tenons through the holes in the said 55 posts G.

To the round I are attached the lower ends of two short bars, K, which have round tenons formed upon their upper ends to enter holes in the lower side of the front round, L, of the 60 seat-frame. To the round L are attached the forward ends of two side bars, M, the rear ends of which are attached to a round, N.

The two rounds L N and the two side bars, M, form the seat-frame. The rear round, N, 65 of the seat-frame has round tenons formed upon its ends, which enter holes formed in the inner sides of the rear posts, A, a little below the lower round, C, of the back-frame.

With this construction, by detaching the 70 rockers H and raising the forward round, L, of the seat-frame off the upper ends of the bars K, the chair can be closed into a compact form for transportation, as shown in Fig. 2, and can be readily put together by the retail 75 dealer or buyer, the various parts, with the exception of the rockers, being permanently connected together.

Having thus described our invention, we 80 claim as new and desire to secure by Letters Patent—

A knockdown rocking-chair on detachable rockers, having the front posts, G, pivoted to the back posts, A, and connected by round I, and a seat hinged to the back and connected 85 detachably with the round I by uprights K, as shown and described.

EUGENE H. CONANT.
GEORGE F. CONANT.
